AMUSEMENT APPARATUS

Bert E. Mills, Oak Park, Ill., assignor to Mills Novelty Company, Chicago, Ill., a corporation of Illinois

Application April 1, 1935, Serial No. 14,100

17 Claims. (Cl. 273—121)

This invention relates to game apparatus and more particularly to check-controlled games in which the results of the play are indicated by suitably placed scoring numerals or by the delivery of tokens, such as metal disks which can be used as checks in the further play of the game, if desired.

One type of machine in which the invention may be embodied is the now well-known pin ball game in which one or more balls are projected upon an inclined board provided with upstanding pins through which a projected ball makes its way in rolling down said board, and either comes to rest in one of a plurality of pockets or seats, all or part of which have scoring or token-delivery values, or rolls down to the lower end of the board if it misses all said pockets or seats.

In the usual form of game of this character the balls which miss the pockets or seats are lost, so far as score or token delivery is concerned, and after the ball or set of balls made available by operation of the check-controlled mechanism has been played, the results, whether successful or unsuccessful, are definitely known and have no effect upon further plays.

In accordance with my invention, however, provision is made for recording and storing up credit for "miss" plays so that, under certain conditions, a number of misses in succession, or in predetermined order, will result in a score or in the delivery of a certain number of tokens, the arrangement being preferably such that upon each play the player either scores or obtains an addition to his credit or "equity", the latter being cancelled only in the event of a scoring or token-delivery play.

Preferably also a visual indicator is employed which serves to inform the player at all times of the amount of his "equity" obtained as a result of unsuccessful plays, the effect of this being that, after a certain number of misses, the player will probably attempt to miss the scoring or token delivery pockets or seats to avoid cancellation of the "equity" and to obtain the score or tokens resulting from a prescribed number of misses.

While I have mentioned particularly the pin ball type of game, and have illustrated my invention as embodied in such a machine, it is to be understood that, in its broader aspects, the invention could be used in other types of games, as, for example, in the spinning reel type of check-controlled game, in which the position of rest of the reels, instead of the final position of the ball or balls in a pin game, would control

the results of the play. It will be apparent that with either type of game the number of tokens delivered may be used instead of numerical legends to indicate the score obtained in the operation of the game.

With the foregoing and other objects in view, which will more fully appear as the description proceeds, the invention resides in the combination and arrangement of parts and in the features of construction hereinafter described and claimed, it being understood that various changes in the embodiment of the invention herein disclosed may be made within the scope of what is claimed and without departing from the spirit of the invention.

Referring to the drawings:

Fig. 1 is a plan view of a pin ball table having the improved token delivery and miss play recording mechanism embodied therein;

Fig. 2 is a bottom plan view of the rack-up mechanism provided for accumulating the miss plays and for actuating the token delivery mechanism after passage of a ball through certain board openings a predetermined number of times;

Fig. 3 is a fragmentary vertical section taken on line 3—3 of Fig. 2;

Fig. 4 is a fragmentary horizontal section taken on line 4—4 of Fig. 2;

Fig. 5 is a perspective view of the rack-up mechanism showing the position assumed by the parts after a ball has passed through a board opening the prescribed number of times necessary to effect delivery of a token through the accumulation of miss plays;

Fig. 6 is a view similar to Fig. 5, with the parts in a different operative position;

Fig. 7 is a detail plan view of one of the ball-operated switches;

Fig. 8 is a transverse section through the ball-operated switch, the view being taken on line 8—8 of Fig. 7; and

Figs. 9 and 10 are wiring diagrams illustrating the circuits employed in operating the recording and token delivery mechanism.

The general construction of pin ball games is well understood in the art and I shall therefore describe only such details thereof as are necessary for an understanding of the relation of such structure to the particular type of game for which the invention is adapted.

Referring particularly to Fig. 1, the pin table consists of side frame members 11 and end frame members (not shown) which provide support for a cover 12 which contains a glass panel 13. A

playing board 14 is positioned in the table frame below panel 13 and, in the embodiment shown, this board is provided with eleven openings, numbered consecutively from 15 to 27, through which a playing ball may pass after being projected onto the board by a plunger 28. Said plunger is provided with an exposed hand piece 29 which may be grasped by the operator to pull out the plunger, the latter when released driving a ball along a chute 31 which connects with a guide channel 43, the latter directing the ball completely around board 14 and thence onto the latter against a spring return arm 36 which checks the roll of the ball and directs it in the general direction of openings 15 and 16. A sliding board 32 (Figs. 7 and 8) is positioned in the table frame below playing board 14, said board being provided below openings 15-25 with elongated openings or slots 33 in which are positioned switches of the form shown in Figs. 7 and 8. Each of these switches consists of a pair of resilient contact arms 34 and 35. The arm 34 is secured to the upper surface of board 32 by rivets 36, and the contact 35 is similarly secured to the lower surface of said board by rivets 37. It will be apparent that a ball rolling through the opening in board 14 will come to rest on the upper contact arm 34, depressing the latter downwardly into engagement with lower contact arm 35, thereby closing an electric circuit, the purpose of which will presently be explained. The ball will rest on contact arm 34 until the operator depresses a lever 38 which, through a series of link connections (not shown) shifts board 32 a distance sufficient to bring the portions of slotted openings 33 which are not covered by arms 34, 35 below the openings in playing board 14. This movement of board 32 removes the ball from its position of rest on contact arm 34, allowing it to fall through slot 33 from whence it is directed to a manually operable ball-elevating plunger 39 which carries it through a guide channel which terminates in a neck piece 41, the latter directing the ball into guide chute 31 at a point slightly in advance of plunger 28.

The mechanism provided for operating board 32 from manually operable lever 38 is not shown, since suitable means for accomplishing this function is well-known in the art. This mechanism is coin-controlled, a coin chute (not shown) being provided which terminates in a slot plate 42 (Fig. 1) through which a coin may be introduced to release a suitable coin-controlled latch which normally prevents operation of lever 38.

From the portion of the apparatus which has been described up to this point, it will be apparent that the general plan of the game consists in projecting a ball onto board 14 through the operation of plunger 28. The ball passes onto the playing board at the upper end of the table after first making one complete circuit of the latter along guide channel 43, and then rolls downwardly over board 14 toward any one of the openings 15-25. After falling through one of these openings the ball remains at rest on one of the switch arms 34 until it is released therefrom as explained through operation of coin-controlled lever 38, after which it may be again projected over the board. It may be added that the board openings 15-25 are or may be provided with triangular shaped guide plates 44 which aid in directing the ball into said openings, and a series of pins 40 may be provided for directing the ball at various angles during the course of its

travel from the upper portion of the board toward openings 26 and 27.

If the ball does not fall through one of openings 15-25, it is directed into either the opening 26 or the opening 27 by a frame plate 45 which is supported through a marginal flange 46 (Fig. 2) in spaced relation above the lower portion of board 14. The under surface of this frame piece is provided with a rim 47, which is arranged to form U-shaped guide channels 48 and 49, which direct the ball into openings 26 and 27, respectively. Ball-operated contact switches 50 and 69, the purpose of which will presently appear, are positioned on board 14 immediately below channels 48 and 49, respectively. These switches are momentarily closed as the ball rolls along said channels toward openings 26 and 27. The ball passing through either the opening 26 or the opening 27 is directed to a trough (not shown) from which it is released upon movement of board 20 32 by the manually operable coin-controlled lever 38.

In accordance with my invention a token delivery mechanism is provided which is arranged to deliver one or more tokens to the operator each time a ball is directed into one of the openings 15-25, and is further arranged to deliver a number of tokens to the operator if he directs a ball a prescribed number of times in succession through either of the openings 26, 27. A totalizer 30 device is also provided for giving a record of the number of times a ball has passed through one of the openings 26 or 27. This device is arranged to be reset to zero position in the event there is an intervening play in which the ball comes 35 through one of the openings 15-25.

Referring particularly to Figs. 2-6, there is provided on the under surface of plate 45 a bracket 51 in which is journaled for free rotation a shaft 52, the upper end of which projects through plate 40 45 to receive a pointer 53, said pointer being secured to shaft 52 through a collar 54. An arcuate scale 55 (Fig. 1), consisting of numerals 0-8 is arranged on the face of plate 45 adjacent the line of movement of the tip portion of pointer 53. 45

The pointer 53 is arranged to be turned in a clockwise direction, viewing Fig. 1, by step movements through one space on the scale 55 each time the playing ball passes through either the opening 26 or the opening 27. The mechanism 50 for accomplishing this comprises: a pair of solenoids 56 and 57, supported in axial alignment from bracket 51 by arms 58 and 59 respectively, said solenoids having a common armature 61; a ratchet 62 consisting of spaced ratchet segments 55 63 and 64 (Fig. 3) fixedly secured to shaft 52; a rack-up arm 65 pivotally supported on shaft 52; a pawl 66, pivoted at 67 to arm 65, for engaging the teeth of 68 of ratchet segments 63; a second pawl 69, pivoted at 71 to bracket 51 for engaging 60 the teeth 70 of ratchet segment 64; an arm 72 fixedly secured at 73 to armature 61, said arm being provided at its lower end with a laterally projecting stud 74, which extends through a notch 75 formed in the lower end of rack-up arm 65. 65

In Fig. 2 the rack-up mechanism is shown with the parts in their normal inoperative position, with solenoids 56, 57 both de-energized. A coil spring 76, connected at one end to a lug 77 carried by rack-up arm 65, and at the other end 70 to bracket 51, urges said arm 65 in a clockwise direction viewing Fig. 2, a lateral projection 78, carried by arm 65, engages against bracket 51 to serve as a stop for limiting the turning of arm 65 under the action of spring 76. A second coil 75

spring 79 extending between a lug 81 on ratchet 62 and a fixed point on bracket 51, urges said ratchet 62 in a clockwise direction, viewing Fig. 2. A lug 82 projecting from the main body portion of ratchet 62 is provided with a shoulder 83 which engages bracket 51 to limit the clockwise turning of ratchet 62 and shaft 52 under the action of spring 79. A small coil spring 84, extending between arm 65 and one arm of pawl 66, urges the latter in a counter-clockwise direction, viewing Fig. 2, thus holding said pawl in yielding engagement with the teeth 68 of ratchet segment 63. A second coil spring 85, having one end connected at 86 to a fixed point on bracket 51 and the other end connected to an arm of pawl 69, urges the latter in a counter-clockwise direction viewing Fig. 5, to hold said pawl in yielding engagement with the teeth 70 of ratchet segment 64.

As will hereinafter appear, solenoid 56 is energized each time switch 50 is closed by passage of a ball into opening 26 and also each time switch 60 is closed by passage of a ball into opening 21. The movement of the several parts of the rack-up mechanism which occur upon each energization of solenoid 56 will be best understood by comparing Figs. 2 and 5. As soon as solenoid 56 is energized armature 61 is moved to the right to displace arm 72 from the position shown in Fig. 2 to the position shown in Fig. 5. This movement of arm 72, through engagement of stud 74 with one edge of the notch 75, causes a counter-clockwise turning of rack-up arm 65 from the position shown in Fig. 2 to the position shown in Fig. 5. This movement of arm 65 advances ratchet 62 and shaft 52 one step in a counter-clockwise direction, viewing Fig. 2, through engagement of pawl 66 with one of the ratchet teeth 68. As soon as solenoid 56 is de-energized armature 61 and arm 72 are returned under the action of coil spring 76, from the position shown in Fig. 5, back to the position shown in Fig. 2, pawl 66 riding over the teeth 68 during this return movement. Ratchet 62 and shaft 52 are prevented from returning to the zero position shown in Fig. 2 through the action of pawl 69 which engages the teeth 70 of ratchet segment 64 (Fig. 6) thus holding the complete ratchet 62 in advanced position. It will thus be apparent that each time solenoid 56 is energized ratchet 62 and shaft 52 and pointer 53, which turn therewith, are turned in a counter-clockwise (Fig. 2) direction by step movements, thus positioning pointer 53 opposite the number on dial 55 which indicates the number of passages of a ball through either of the openings 26 or 27. In the particular embodiment shown scale 55 is provided with eight numbers and ratchet 62 is similarly provided with eight teeth, the arrangement being such that after eight successive energizations of solenoid 56 ratchet 62 will have been turned from the position shown in Fig. 2 to the extreme advanced position shown in Fig. 5. In this advanced position a stud 87 which is carried by the lug portion 82 of ratchet 62 moves into position to close a switch 88 which, as will hereinafter appear in the descriptions of Figs. 9 and 10, serves to energize an electric circuit which actuates the token delivery mechanism. Switch 88 consists of resilient contact arms 89 and 91 which are secured by bolts 92 to a switch plate 93, the latter being mounted on the under face of plate 45. It will be evident from Fig. 5 that when ratchet 62 is moved into the last position, corresponding to the position 8 on the dial 55, stud 87 will move

against contact arm 89 to effect closing of switch 88.

The purpose of solenoid 57 is to cause return of ratchet 62 and pointer 53 to the zero position in the event that the operator directs a ball into one of the openings 15-25 before producing eight successive energizations of solenoid 56. As will more fully appear in the description of Figs. 9 and 10, passage of a ball into any one of the openings 15-25 will result in actuation of a token delivery mechanism which delivers one or more tokens to the operator. In the particular embodiment shown the delivery mechanism which is operated by closure of switch 88 is intended to operate only in the event that there is no intervening passage of a ball through one of the openings 15-25 before completion of the necessary eight passages of a ball through openings 26, 27. To produce this result solenoid 57 is arranged to be energized each time the operator directs a ball into one of the openings 15-25 after the ratchet 62 has been moved from its zero position. A switch 94 (Fig. 2) consisting of resilient contact arms 95 and 96 is supported on switch plate 93, the arm 95 having an extension 90 which is engaged by stud 87 to hold the switch open when ratchet 62 is in the zero position shown in Fig. 2. As soon as ratchet 62 moves away from zero position contact arm 95 moves into the circuit closing position shown in Fig. 5. As will hereinafter appear, this preliminary closing of switch 94 places the circuit which energizes solenoid 57 in condition for closing each time a ball passes through one of the openings 15-25 to close one of the switches associated with said openings. Solenoid 57 effects a return of ratchet 62 and pointer 53 to zero position by pulling armature 61 to the left from the position shown in Fig. 2 to the position shown in Fig. 6. This movement causes stud 74, carried on the lower end of arm 72, to strike the lower arm portions 97 and 100 of pawls 66 and 69, respectively, thus pivoting said pawls in a counter-clockwise direction and removing them from engagement with their respective ratchet segments. Solenoid 57 remains energized for a short space of time through the provision of a wiping contact, which will be hereinafter described, so that pawls 66 and 69 are held from engagement with ratchet segments 63 and 64, respectively, for an interval of time sufficient to allow spring 79 to return the ratchet 62 and shaft 52 to the zero position. After solenoid 57 is de-energized the system of springs 76, 79, 84 and 85 serve to return armature 61 from the position shown in Fig. 6 back to the position shown in Fig. 2. Solenoid 57 thus makes it impossible to close switch 88 unless there have been eight consecutive actuations of the rack-up mechanism without the intervening passage of a ball through one of the openings 15-25.

The token delivery mechanism and the control circuits associated therewith are illustrated in Figs. 9 and 10. Inasmuch as the mechanical construction of means for dispensing one or more tokens through the use of suitable spring actuated slides is well-known in the art, I have only made a diagrammatic showing of this portion of the mechanism and I have likewise merely given a diagrammatic showing of the coin-controlled means for resetting such slides inasmuch as the construction of mechanism for accomplishing this function is also well understood in the art. In Figs. 9 and 10 I have shown a delivery mechanism consisting of four slides 98, 99 and 100 and 101, which are slidably mounted on a plate 75.

102 above which is supported a series of tubes 103 in which are stacked the tokens which are dispensed by the slides 98—101. Solenoids 104, 105, 106 and 107 are associated with slides 98—101, respectively, the armatures 108 of each of the solenoids being pivotally connected with spring held latch levers 109 which engage over studs 111 carried by the dispensing slides to hold the latter in retracted position against the tension of springs 112 which extend between studs 111 and plate 102. It will be evident that when solenoid 104, for example, is energized slide 98 will be released and retracted by spring 112 to effect delivery of a token. These slides are reset through coin-controlled manually operable lever 38 which operates a reset bar 113 (shown in dotted lines in Fig. 10), said bar being provided with studs 114 which engage against the slides to move them back to latched position when bar 20 113 is moved toward the left, viewing Fig. 10.

The token delivery slides and associated solenoids for operating the same may be conveniently mounted in a housing 115 which is placed in the front portion of the table frame, the tokens which are delivered from magazines 103 being directed to the operator through a suitable delivery chute 116 which projects from a wall of the table frame (Fig. 1). In the particular embodiment shown the slides 99, 100 and 101 are arranged to deliver two, four and eight tokens, respectively, upon each actuation thereof. Slide 98 is arranged to deliver ten tokens each time it is operated. If desired, these tokens may be of such form as to permit their use in lieu of a coin in coin slot 42.

35 I shall now describe the circuit connections shown in Figs. 9 and 10 whereby the slides 98—101 are operated upon passage of a ball through openings 15—27. Current is supplied from a battery of dry cells, which are supported in the table frame, through main line wires 117 and 118 to a switch panel 119 having seven terminals 120—126, which connect through jumpers 127 with corresponding terminals 128—134, the latter being carried on a second switch panel 135. The lower contact arms 35 of the switches associated with openings 12—25, and also one of the contact arms of each of switches 50 and 60, are connected to main line wire 117 through contacts 129, 128 and a wire 136, the latter also feeding switch arms 91 and 96 of switches 88 and 94, respectively.

50 Board openings 15, 17, 19, 21, 23 and 25 are each arranged to operate slide 99 which delivers two tokens. This is accomplished through energization of solenoid 105, and the circuit through this solenoid is traced from line 117 through contacts 120, 128 and line 136 to any one of the switch arms 35 of the group of openings 15, 17, 19, 21, 23 and 25, and thence through the corresponding upper contact arm 34 to a wire 137 which connects through contacts 130 and 122 with a wire 138, the latter leading to the solenoid 105, the return from the latter being through a wire 139 which connects through a switch 141 and a wire 142 with the other side of the main line, 118.

The switches associated with the group of openings 18, 20, 22 are designed to operate delivery slide 100 which dispenses four tokens upon each energization of solenoid 106. The circuit through this solenoid is traced from line wire 117 through contacts 120, 128 and wire 136 to lower switch arms 35, and thence from any one of the upper switch arms 34 to a wire 143 which connects through terminals 131 and 123 with a

wire 144, the latter connecting with solenoid 106, the return being through wire 139, switch 141, and wire 142, to the other side of the line, 118.

The switch associated with opening 24 is arranged to operate slide 98 which delivers ten tokens upon each energization of solenoid 104. This circuit is traced from main line 117 through terminals 120, 128 and line 136 to switch arm 35, and thence through upper switch arm 34 and a wire 145 to terminal 129 which connects through terminal 121 with a wire 146, the latter leading to solenoid 104, the return from said solenoid being through wire 139, switch 141, and wire 142, to the opposite main line wire 118.

Slide 101, which delivers eight tokens upon each energization of solenoid 107, is arranged to be operated by two independent circuits. The first of these circuits is through the ball-actuated switch associated with board opening 16. This circuit is traced from main line wire 117 through terminals 120, 128, and wire 136, to switch arm 35, and thence from switch arm 34 through a wire 147 which connects through terminals 132 and 124 with a wire 148, the latter leading to solenoid 107, the return from this solenoid being through wire 138, switch 141, and wire 142 to the other side of the main line, 118. Slide 101 will be thus operated each time a ball is placed in board opening 16 to deliver eight tokens. The slide 101 is also arranged to be operated upon the closing of switch 38 which takes place, as previously explained, after the rack-up mechanism has been actuated eight successive times by the passage of a ball through either opening 26 or opening 27. This circuit through switch 38 is traced from main line wire 117 through terminals 120, 128 and wire 136, to switch arm 91 and thence through switch arm 89 and a wire 149 to terminal 132, which, as explained, connects through terminal 124 and wire 148 to solenoid 107. In other words, the switch associated with opening 16, and switch 38 which is closed by the rack-up mechanism, are in parallel so that the closing of either energizes solenoid 107 independently of the other, there being thus two distinct types of play which may result in the operation of the eight token slide 101.

55 As previously explained solenoid 56 is energized to actuate the rack-up mechanism each time a ball passes into either the opening 26 or the opening 27 to close either the switch 50 or the switch 60. The circuit through solenoid 56 is traced from main line wire 117 and terminals 120, 128 to wire 136 which feeds the lower contact arms of switches 50, 60, and from either of the latter the circuit is traced through a wire 151 to solenoid 56, from which the return is carried through a wire 152 and switch terminals 133, 125 to main line wire 118. Closure of the switch associated with either of the openings 26 or 27 will thus energize solenoid 56 to produce movement of ratchet 62 and pointer 53 one step away from zero position. After eight consecutive energizations of solenoid 56 have been effected, switch 88 is closed by ratchet 62 to effect operation of slide 101.

60 The circuit through solenoid 57 is so arranged as to effect energization of the latter each time one of the slides 98—101 is operated. As previously explained, solenoid 57 operates to return ratchet 62 to zero position after the latter has been displaced from zero position through the operation of solenoid 56. As soon as ratchet 62 is moved one step away from zero position, switch 94 is closed through removal of stud 87 from en- 75

gagement with the extended portion 90 of switch arm 95. This circuit through solenoid 57 is traced from main line wire 117, terminals 120, 128 to wire 136, which connects with switch arm 96, from which point the circuit is carried through switch arm 95 and a wire 153 to solenoid 57 which is connected through a wire 154 with terminal 134, the latter connecting with terminal 126. A wire 155 connects terminal 126 with plate 102 which supports slides 98-101, each of the latter being in electrical contact with plate 102. Each of the slides 98-101 is provided with a switch point 156 which, upon the delivery stroke of the slide, moves into wiping engagement with a switch arm 157. Each of arms 157 connects through a common return wire 158 with wire 142 which leads to main line wire 118. It will be apparent that after preliminary closing of switch 94 movement of any one of the delivery slides 98-101 through an active stroke will complete the circuit through solenoid 57 by reason of the closure of one of the switches 156, 157. It will be noted from Fig. 10 that the switch points 156 will remain in engagement with switch arms 157 for a sufficient length of time to keep solenoid 57 energized until ratchet 62 is returned to the zero position. This circuit arrangement thus requires eight consecutive movements of ratchet 62 and pointer 53 away from the zero position to effect closing of switch 88. If there is an intervening actuation of any one of the delivery slides 98-101, ratchet 62 and pointer 53 are returned to zero position, and will again require eight consecutive movements to effect closure of switch 88.

In order to prevent the energizing circuit from remaining closed after operation of one of the delivery slides and before removal of the ball from its circuit closing position on one of the switch arms 34, I provide a circuit breaking device for opening switch 141 each time one of the slides 98-101 is moved through a delivering stroke. Any convenient form of switch breaking device may be used. In the embodiment shown I provide an arm 159 (Fig. 10), pivoted at 161 to a suitable frame support, and provided with spaced laterally projecting posts 162 which are positioned to be engaged by slides 98-101 upon movement of any one of the latter through an active stroke. A coil spring 163 normally holds pivoted arm 159 in the position shown in Fig. 10 in which position the contacts of switch 141 are closed. Movement of any one of the slides 98-101 into engagement with one of the posts 162 will serve to open switch 141 by pivoting arm 159 into open circuit position. Opening of switch 141 de-energizes each of solenoids 104-107, thus preventing the circuits associated with openings 15-25 from remaining closed after a ball has been directed into one of said openings and before it has been removed by a subsequent coin actuation of the machine in the manner previously explained.

As shown in Fig. 1, the openings 15-25 may be provided with numerals identifying each opening with the number of tokens delivered when a ball is placed therein. When the game is used without the token delivery mechanism these numerals may be used to calculate the score made by the operator, in which case, for example, a prescribed number of miss plays accumulated on scale 55 could be considered as having a certain scoring value which would be taken into account, along with the values ob-

tained on the scoring plays, in computing the final score.

The manner of playing the game may be briefly described as follows: assuming pointer 53 is in the zero position, the operator first introduces a suitable coin into coin slot 42, whereupon lever 38 may be operated to release the ball from board 32. By pushing inwardly on plunger 39 the ball thus released is positioned in front of plunger 28 from which point it is projected over board 14. If the ball happens to roll into one of the openings 15-25 it operates one of the token delivery slides 98-101 to deliver two or more tokens depending upon the particular opening into which the ball falls. If the ball fails to pass into one of the openings 15-25 it rolls into either the opening 26 or the opening 27 to produce one energization of solenoid 56 which results in movement of pointer 53 one step in a clockwise direction, viewing Fig. 1. Pointer 53 in this position indicates to the operator that he has accomplished one of the necessary eight plays which are required to operate the eight token delivery slide 101.

Play of the game is repeated in this manner, the number of tokens delivered depending upon the particular openings into which the ball is directed upon the successive plays. If there are eight consecutive plays in which the operator fails to put the ball into one of the openings 15-25, pointer 53 will be moved opposite the numeral 8 on scale 55 and upon the eighth play, which brings pointer 53 to that position, switch 88 will be closed by the rack-up mechanism to effect actuation of the eight token slide 101. If, however, the operator happens to place a ball in one of the openings 15-25 before pointer 53 has reached its eighth position, said pointer, together with ratchet 62, will be returned to zero position through the operation of solenoid 57 which is energized each time one of the slides 98-101 operates. Any partial accumulation of credit plays on the scale 55 is thus rendered ineffective by the intervening passage of a ball through one of the openings 15-25. However, the operator is at all times apprised of the number of plays which are still necessary to operate the eight token slide 101 through passages of a ball through either the opening 26 or the opening 27.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. A check-controlled game comprising an actuator, a member adapted to be set in motion thereby and to come to rest at one of a number of possible positions, token delivery mechanism, means controlled by said member when at certain of said positions for operating said delivery mechanism, a totalizer, means controlled by said member when at other positions for operating said totalizer, and means controlled by the totalizer, after it has been operated a predetermined number of times in immediate succession, for operating said token delivery mechanism.

2. A check controlled game comprising an actuator, a member adapted to be set in motion thereby and to come to rest at one of a number of possible positions, token delivery mechanism, means controlled by said member when at cer-

- tain of said positions for operating said delivery mechanism, a totalizer, means controlled by said member when at other positions for operating said totalizer, means controlled by the totalizer, after it has been operated a predetermined number of times, for operating said token delivery mechanism, and means operable by actuation of said delivery mechanism for restoring said totalizer to initial position.
- 10 3. A check-controlled game comprising an actuator, a member adapted to be set in motion thereby and to come to rest at one of a number of possible positions, token delivery mechanism, means controlled by said member when at certain of said positions for operating said delivery mechanism, a ratchet device, means controlled by said member when at other positions for operating said ratchet device, means controlled by the ratchet device after it has been operated a predetermined number of times in immediate succession for operating said token delivery mechanism, and a dial indicator movable by said device for indicating the number of times the latter has been operated without an intervening operation of said delivery mechanism.
- 15 4. A check-controlled game comprising an actuator, a member adapted to be set in motion thereby and to come to rest at one of a number of possible positions, token delivery mechanism, means controlled by said member when at certain of said positions for operating said delivery mechanism, a totalizer, means controlled by said member when at other positions for operating said totalizer, and means controlled by the totalizer, after it has been operated a predetermined number of times successively, for operating said token delivery mechanism.
- 20 5. In an amusement apparatus, the combination with a check-controlled playing mechanism, including a playing element adapted to be moved to one of a plurality of possible positions, of means for delivering a token to the operator upon each play which results in movement of said element to certain of said positions, and means for operating said delivery means after a predetermined number of consecutive plays each of which effects movement of said element to certain of the other positions to which the same may be moved.
- 25 6. In a pin ball game, the combination with a playing board having openings therein for receiving a ball projected over the surface of the board and check-controlled means for returning a played ball to position for another projection over the board, of means for delivering a token to the operator upon each passage of a ball into certain of said openings, and means for operating said delivery means after a predetermined number of passages of a ball into certain of the other openings without the intervening passage of a ball into one of said first mentioned openings.
- 30 7. In a pin ball game, the combination with a playing board having openings therein for receiving a ball projected over the surface of the board and check-controlled means for returning a played ball to position for another projection over the board, of means for delivering a token to the operator upon each passage of a ball into certain of said openings, means for operating said delivery means after a predetermined number of passages of a ball into certain of the other openings without the intervening passage of a ball into one of said first mentioned openings, and a totalizer device for indicating, after any

particular play, the number of plays still required to result in actuation of said delivery means by consecutive passages of a ball into said last mentioned openings.

8. A game apparatus comprising a board having a plurality of pockets therein, means for projecting a ball onto said board and into one or another of said pockets, a check-dispensing mechanism, means actuated by the ball when it enters certain of said pockets for operating said check-dispensing mechanism to cause the same to dispense a predetermined number of checks, which may vary according to the pocket in which the ball is placed, check-controlled means for holding the ball in the pocket in which it comes to rest and for releasing it for return to the projecting means, one or more other pockets being positioned to receive a played ball if it misses the previously described pockets, a device movable step by step through a series of positions and adapted to be advanced one step each time a ball enters said last-identified pocket or pockets, said device causing operation of said dispensing mechanism to cause the same to dispense a predetermined number of checks after the device has been advanced a certain number of steps, and means operated by a ball entering one or another of said first-described pockets before said device has caused actuation of said dispensing mechanism for returning the device to its original position, thereby cancelling the advance previously made toward the position in which the device causes operation of the dispensing mechanism.

9. A check-controlled game, comprising an actuator, a member adapted to be set in motion thereby and to come to rest at one of a number of possible positions, some of which are scoring positions, and at least one of which is a non-scoring position, means controlled by said member when it stops at a scoring position, for indicating a primary scoring value, means controlled by said member when it stops at a non-scoring position, for totalizing non-scoring plays, so as to accumulate an equity toward a secondary score, means for causing such secondary score to be indicated when a predetermined total of consecutive non-scoring plays has been totalized, and for simultaneously resetting said totalizing means back to zero, and means for resetting said totalizing means back to zero and cancelling said equity when said element stops at a scoring position.

10. A check-controlled game, comprising an actuator, a member adapted to be set in motion thereby and to come to rest at one of a number of possible positions, some of which are scoring positions, and at least one of which is a non-scoring position, means controlled by said member when it stops at a scoring position, for indicating a scoring value, means controlled by said member when it stops at a non-scoring position for totalizing non-scoring plays without indicating a scoring value, means controlled by said totalizing means when a given total of non-scoring plays has been totalized, for indicating a scoring value, and means for resetting said totalizing means back to starting position upon either of the aforesaid indications of scoring value.

11. A check-controlled game, comprising an actuator, a dispenser, a member adapted to be set in motion by said actuator and to come to rest at one of a number of possible positions, some of which are scoring positions, and at least one

of which is a non-scoring position, means controlled by said member when it stops at a scoring position for actuating said dispenser, means controlled by said member when it stops at a non-scoring position for totalizing consecutive non-scoring plays, means controlled by said totalizing means when a given total of non-scoring plays has been totalized, for actuating said dispenser, and means for setting said totalizing means back to starting position upon either of the aforesaid actuations of the dispensing means.

12. A check-controlled game, comprising an actuator, a dispenser, a member adapted to be set in motion by said actuator and to come to rest at one of a number of possible positions, some of which are scoring positions, and at least one of which is a non-scoring position, means controlled by said member when it stops at a scoring position for actuating said dispenser to effect a delivery therefrom, a device adapted to be advanced step by step from an initial position to a position in which it actuates said dispenser independently of the aforesaid actuating means, means controlled by said member when in a non-scoring position, for advancing said device, and means for setting said device back to its initial position upon either of the aforesaid actuations of the dispenser.

13. In a pin ball game, the combination of a playing board having a plurality of openings therein for receiving a ball projected over the surface of the board, some of said openings being scoring openings, and at least one of said openings being non-scoring, a device for totalizing the passage of balls into said non-scoring opening without indicating a score, and means for indicating a score each time a ball enters a scoring opening, said means being additionally operated to indicate a score, by said device when the latter has totalized a predetermined number of consecutive non-scoring plays.

14. In a pin ball game, the combination of a playing board having a plurality of openings therein for receiving a ball projected over the surface of the board, some of said openings being scoring openings, and at least one of said openings being non-scoring, a device for totalizing the passage of balls into said non-scoring opening without indicating a score, a dispenser, means for operating said dispenser each time a ball enters a scoring opening, and means for operating said dispenser when said device has totalized a predetermined number of non-scoring plays.

15. In a pin ball game, the combination of a playing board having a plurality of openings therein for receiving a ball projected over the surface of the board, some of said openings being scoring openings, and at least one of said openings being non-scoring, a device for totalizing the passage of balls into said non-scoring opening without indicating a score, and means for indicating a score each time a ball enters a scoring opening, said device comprising a ratchet, means for advancing said ratchet each time a ball enters said non-scoring opening, and an indicator movable by said ratchet for indicating the number of times the latter has been actuated.

16. In a pin ball game, the combination of a playing board having a plurality of openings therein for receiving a ball projected over the surface of the board, some of said openings being scoring openings, and at least one of said openings being non-scoring, a device for totalizing the passage of balls into said non-scoring opening without indicating a score, means for indicating a score each time a ball enters a scoring opening, said means being additionally operated to indicate a score, by said device when the latter has totalized a predetermined number of non-scoring plays, and means operated upon each indication of a score, for setting said device back to initial position.

17. In a check-controlled game having a member adapted to be set in motion and to come to rest at one of a number of possible positions, some of which are scoring positions and at least one of which is a non-scoring position, a ratchet, an advancing pawl and a holding pawl for said ratchet, electromagnetic means, controlled by said member when in a scoring position, for driving said advancing pawl so as to advance said ratchet one step, means resiliently urging said ratchet toward its initial position, electromagnetic means, controlled by said member when in a non-scoring position, for releasing both of said pawls from engagement with the ratchet and allowing the latter to return to its initial position, a check dispenser, electromagnetic means for actuating said dispenser, means controlled by said member when in a scoring position, for energizing said dispenser-actuating means, and means including a switch adapted to be engaged by said ratchet when the latter has moved a predetermined number of steps and thereby closed so as to independently energize said dispenser-actuating means.

BERT E. MILLS.
